(57) **CLAIM**

The ornamental design for a wrench, as shown and described.

DESCRIPTION

FIG. 1 is a perspective view of a wrench according to the invention illustrating the top, rear and right sides of the wrench;

FIG. 2 is a perspective view of the wrench of FIG. 1;

FIG. 3 is a ride side elevation view of the wrench of FIG. 1;

FIG. 4 is a left side elevation view of the wrench of FIG. 1;

FIG. 5 is a top plan view of the wrench of FIG. 1

FIG. 6 is a bottom plan view of the wrench of FIG. 1;

FIG. 7 is a front elevation view of the wrench of FIG. 1; and,

FIG. 8 is a section view of the wrench taken along the line 8-8 of FIG. 7.

The broken lines shown on the drawings are included for the purpose of illustration only and form no part of the claimed design.

1 Claim, 6 Drawing Sheets
